UNITED STATES PATENT OFFICE.

GEORGES NUYTS, OF PARIS, FRANCE.

TOOTHBRUSH.

Application filed May 10, 1927, Serial No. 190,272, and in France April 6, 1927.

This invention has for object a tooth-brush in which the handle and the brush proper are independent from each other. The brush, rendered removable, can thus, when its hair or bristles are worn out, be easily separated from the handle and replaced by a new brush.

The invention is essentially characterized by the particular method of assemblage and clamping of the brush body, removable from the handle. This assemblage, in which intervene only parts of simple construction, is very easily and rapidly effected.

The invention is illustrated in the accompanying drawing giving, by way of example only, a typical form of construction.

Fig. 1 is an elevation of the assembled tooth-brush.

Fig. 2 is a longitudinal section thereof made according to line A—B of Fig. 1.

Fig. 3 is a side view of the brush head.

Fig. 4 is a view of the handle.

Fig. 5 is an end view of the handle, on the side which receives the brush head.

In the figures of the drawing is seen the body of the brush head 1 with its hair or bristles 2; this body, which will have all suitable dimensions and the shape of which will generally be that shown in the drawing, is provided with a longitudinal channel 3 and has, at its opposite ends, two grooves 4, 4' the bottoms of which are constituted by two flat portions 5, 5'. The handle 6, perforated with a channel 7 forming an extension of the channel of the brush 3 and which widens at 8, near the rear part of the handle, receives at its end 6'' one of the flat portions 5 or 5' of the brush, which latter can be mounted on one side or the other.

The assemblage is effected through two intermediate members. One of these members is provided with a head 9 taking a bearing against the flat part 5 or 5' and carrying a rod 10 which fits in the channels 3 and 7; the other member 11 constituting a pulling rod terminated by a milled knob 12 fits in the enlarged portion 8 of the channel of the handle and receives in an internally screw-threaded end portion 13, the screw-threaded end 14 of the bearing rod 10.

Finally, the front end of the handle is provided with a rounded portion 6' capable of fitting about the contour of the brush body and on which projects the rectangular boss 6'' which can fit on the flat portion 5 (or 5').

The operation of assemblage of the brush,

the constituent elements of which have just been described will be easily understood. The bearing rod 10 having been introduced in the channel 3, it is engaged into the channel 7, so that the boss 6'' comes into contact with the flat portion 5 at the bottom of the groove 4 or 4'.

The pulling rod 11 is then slid in the open portion 8 of the handle until its end encounters the screw-threaded part of the rod 10. By then turning the rod 11 through the medium of its operating milled knob, this rod is screwed on the preceding one until the head 9 exerts on the end of the brush body a sufficient stress for causing this body to perfectly fit against the handle and to be rendered rigid with the latter.

The tooth-brush is taken to pieces with the same facility by the reverse operation.

It will be seen that an important advantage of the above described tooth-brush, resides in the fact that, on the same handle can be fitted brushes of different lengths; according to the length of the brush to be mounted on the handle, the rod 10 enters more or less into the channel 7 and, consequently, these differences of length are compensated when the milled knob 12 is screwed completely home. This knob will therefore be screwed more or less according as a small, middle size or large brush will be fitted on the handle.

Various modifications can be provided; for instance, the inner screw-threads might be formed on the rod 10 and the outer screw-threads on the pulling rod 11, but this form of construction which would necessitate giving to the channel 3 a great diameter, is less practical than the preceding one.

It is to be understood that this brush, body or handle, can be made of any desirable materials, metal, as for instance aluminium, or bone, moulded plastic materials, galalith, etc. and that it can receive any desirable shapes or decorations, the invention residing in the principle of assemblage and of clamping of the brush body proper on the handle by means of two intermediate members screwing on each other.

Claims:

1. A tooth brush comprising a brush head provided with a longitudinal channel and provided with identical recesses at the respective ends intersecting the channel, a handle provided with a longitudinal channel, engaging means on one end of the handle

complementary to either of the recesses in the head for interengagement with one of said recesses when the handle and head are interengaged with each other, and interengaged fastening elements arranged throughout both of the channels and including a stop head adapted to be countersunk in the outer recess in the head, substantially as and for the purposes set forth.

10 2. A tooth brush as claimed in claim 1 wherein the engaging means on the handle

includes opposed bosses on opposite sides of the bore for engagement with either of the recesses in the brush head and recessed portions for engaging the adjacent portions of 15 the brush head, substantially as and for the purposes set forth.

The foregoing specification of my "tooth-brush" signed by me this 26th day of April, 1927.

GEORGES NUYTS.
